US00D786385S

(12) **United States Design Patent** (10) **Patent No.:** **US D786,385 S**
(45) **Date of Patent:** **** May 9, 2017**

(54) **TRIGGER GUARD FOR A REVOLVER**

(71) Applicant: **Kimber IP, LLC**, Yonkers, NY (US)

(72) Inventors: **Daniel Edward Sapiro**, Mount Vernon, NY (US); **Ronald Richard Dudzic, Jr.**, Tarrytown, NY (US); **Lucio DiTrolio**, Mineola, NY (US)

(73) Assignee: **Kimber IP, LLC**, Yonkers, NY (US)

(**) Term: **15 Years**

(21) Appl. No.: **29/551,888**

(22) Filed: **Jan. 18, 2016**

(51) LOC (10) Cl. **22-01**

(52) U.S. Cl.

USPC **D22/108**

(57) **CLAIM**

The ornamental design for a trigger guard for a revolver, as shown and described.

DESCRIPTION

FIG. 1 is a front, top, left side perspective view of a trigger guard for a revolver showing our new design;

FIG. 2 is a rear, bottom, right side perspective view thereof;

FIG. 3 is a front, elevation view thereof;

FIG. 4 is a rear elevation view thereof;

FIG. 5 is a left side, elevation view thereof;

FIG. 6 is a right side, elevation view thereof;

FIG. 7 is a top, plan view thereof; and,

FIG. 8 is bottom, plan view thereof.

The broken lines in the figures are used to illustrate environment, in which the claimed design is embodied, and form no part of the claimed design.

1 Claim, 8 Drawing Sheets
